UNITED STATES PATENT OFFICE.

WILLIAM McNORTON, OF THOMPSON FALLS, MONTANA.

RAIL-CLAMP.

1,207,961.

Specification of Letters Patent. Patented Dec. 12, 1916.

Application filed September 16, 1915. Serial No. 51,073.

To all whom it may concern:

Be it known that I, WILLIAM McNORTON, a citizen of the United States, residing at Thompson Falls, in the county of Sanders, 5 State of Montana, have invented certain new and useful Improvements in Rail-Clamps; and I do hereby declare the following to be a full, clear, and exact description of the invention, such as will 10 enable others skilled in the art to which it appertains to make and use the same.

This invention relates to improvements in rail clamps.

One object of the invention is to provide 15 a novel and efficient rail clamp which obviates the use of fish plates and bolts in connection with joints.

Another object is to provide a device of 20 this character which is adapted to be used in connection with wooden ties already placed in the road bed.

Other objects and advantages will be apparent from the following description when 25 taken in connection with the accompanying drawing.

In the drawing: Figure 1 is a top plan view of one form of my rail clamp, Fig. 2 is a longitudinal section on the line 2—2 of Fig. 1, Fig. 3 is a horizontal section on the 30 line 3—3 of Fig. 2, Fig. 4 is a side elevation showing the rails in section, Fig. 5 is a side elevation of a modified form, and Fig. 6 is an elevation of the same form from the other side of the device.

35 Referring particularly to the accompanying drawing, and especially to Figs. 1, 2, 3, and 4, 10—10 represents a pair of metal tie members which are adapted to be placed on the ordinary wooden tie or to be mounted 40 on the road bed. It will of course be understood that one of these metal members is disposed at each end and is adapted to support the meeting ends of the rails 11. The members 10 are each formed with a pair of 45 upwardly and inwardly directed flanges 12 and 13 under one of which is disposed one side of the flanges of the ends of the rails 11. Formed on the upper side of the flange 12 is a vertical extension 15 which carries a plurality of pins 16 adapted to be received 50 in the openings in the webs of the rails.

A plate 17 is slipped in between the rail and the flange 13 and has formed on one side a longitudinal rib 18 which is received 55 under the flange 13, while the opposite side

is formed with a longitudinal groove 19 receiving the remaining side portion of the base of the rail. A vertical flange 20 extends upwardly from the inner portion of the plate 17 and bears against the sides of 60 the rails opposite to the extension 15. A head 21 is formed on one end of the member 17 to limit the inward movement thereof, while on the other end is a turn button 22 adapted to be swung into a depending position against the adjacent side of the member 65 10 to prevent the member 17 from movement in the opposite direction. The member 17 is narrower at one end than at the other so that it will wedge in between the rail and 70 flange 13 and thus hold the rail or rail ends against sidewise movement or against creeping.

It will be noted that the turn button 22 is reduced at its outer end portion whereby it 75 will readily pass under the flange 13 when the member 17 is being slipped into place. Formed on the inner end of each of the members 10 is a transverse centrally disposed web which is straddled by the bifurcated ends of the arms of a screw or bolt 24, said arms being secured thereto by the vertical pins 25. The other or threaded ends of the bolts are oppositely threaded and engaged with a nut 26 whereby a turn buckle 80 85 is formed. By means of this turnbuckle the rails can be adjusted to their properly spaced position and firmly held in such position.

In Figs. 5 and 6, there is shown a form 90 of rail clamp in which the flange 12' does not have a vertical extension as in the first form. There is a sliding member 17' similar to the member 17 and provided with a turn button 22'. In this form the supports 95 and clamps for the rail are connected by an integral bar piece 10' which forms a portion of the tie itself and may be used by itself or in connection with the wooden tie.

100 What is claimed is:

A rail clamp comprising a plate adapted to be secured to a tie and having a rail base engaging flange thereon, a flange carried by the plate at the opposite side of the rail and spaced therefrom, said flange having a 105 longitudinal tapering groove formed therein, a tapering rail base engaging bar slidable between the flange and the rail and formed with a rib engaging in said groove, and a turn button on one end of said bar ar- 110

ranged to be turned to engage one side of the said plate to prevent backward movement of the bar, said turn button being arranged to be turned into a horizontal position and having its outer end reduced to be snugly received within the groove when the bar is being inserted or removed.

In testimony whereof, I affix my signature, in the presence of two witnesses.

WILLIAM McNORTON.
